Primary Examiner—Cathy Anne MacCormac

(57) **CLAIM**

The ornamental design for a litter box, as shown and described.

DESCRIPTION

FIG. 1 is a front perspective view showing my new design;

FIG. 2 is a top plan view thereof;

FIG. 3 is a left side elevational view thereof; and,

FIG. 4 is a right side elevational view thereof.

A bottom view of the litter box is not provided, as it is not part of the design sought to be patented.

1 Claim, 4 Drawing Sheets

FIG. 1

FIG. 2

FIG. 3

FIG. 4
